UNITED STATES PATENT OFFICE.

JOHN HILGERT, OF CHICAGO, ILLINOIS.

TYPEWRITER.

Application filed July 6, 1925. Serial No. 41,586.

This invention relates generally to improvements in typewriters and has particular reference to improved means for quickly releasing two or more type bars or hammers which frequently become jammed together during the rapid operation of the typewriter.

It is an object of this invention to provide a comparatively simple mechanism which can readily be adapted to new or existing typewriters and which mechanism will not only obviate the soiling of the operator's hands in separating or releasing the two contacting type bars, but which improved mechanism will increase the efficiency of operation by facilitating the speed of operation, since the present time consuming operation to release the jammed type bars will be reduced to a minimum.

The speed of operation of a typewriter with the improvement here disclosed will be particularly apparent where the "touch" system of operation is employed.

It is also an object of this invention to provide a mechanism of this character which shall be comparatively simple in construction and flexible in operation.

With these and other objects in view, my invention consists in the novel combination, construction and arrangement of the parts and members shown in the accompanying diagrammatic drawings, described in the following specifications and particularly pointed out in the appended claim.

Referring to the diagrammatic illustrations:

Fig. 1, is a plan view of a typewriter embodying my invention;

Fig. 2, is a cross sectional view of Fig. 1;

Fig. 3, is an enlarged side elevation of my improved mechanism, and

Fig. 4, is a plan view of the mechanism shown in Fig. 3.

Referring more particularly to the diagrammatic illustrations, 10 indicates a typewriter having sides 10^A and a platen 11. The type bars 12 are shown here pivotally mounted on the segmental bearing 13 and adapted for operation by the keys 14 through suitable mechanisms indicated generally by numeral 15 having segmental racks 16 which operatively engage the segmental gear-like teeth 17 on the pivotal portion of the type bars. The space bar is indicated by numeral 18.

As above pointed out, it frequently occurs that when the keys 14 are rapidly operated,

two of the type bars, and sometimes three of the type bars will engage in jammed contact just over the platen 11 as shown in the illustrations, thus interfering with and stopping the operation of the typewriter until released by the hands of the operator.

The improved release mechanism comprises a pair of supports 19 of U or channel cross section provided with bolts 20 for attachment to the inner face of the sides 10^A of the typewriter.

An arm 21 is pivotally mounted on the pin 22 on the inner upstanding leg of each support 19 and a cross release bar or contact member 23, preferably of inverted U cross section extends between said arms 21 and is securely attached to their free ends.

Operating levers 24 are pivotally mounted on the pins 25 and extend below the keys 18 having terminal operating keys 24^A. In order to afford a simultaneous movement of both operating levers 24 when either of said keys 24^A is operated, I preferably connect same by a cross bar 26, also of inverted U cross section.

If desirable, an intermediate key 27, could readily be attached to the cross bar 26, as shown by dotted lines in Figs. 1 and 2.

The inner ends of the levers 24 are operatively connected by a link 28 to the pivoted arms 21 and coil springs 29 normally retain the arms 21 and levers 24 in the lower inoperative position as shown in Fig. 3.

It will now be readily apparent that when two or more type bars 12 have been brought into inoperative contact with each other as shown in Figs. 1 and 2, that the downward movement of the key ends 24^A will move the lever 24 about their pivotal supports 25 to thereby raise their inner ends and through the connecting links cause an upward movement of the free ends of the arms 21 with the interconnected release bar 23, which bar 23 will engage the lowered key levers 15^A 100 of the respective contacting type bars 12 to thereby release their engagement.

I claim:

In a typewriter having a plurality of pivoted type-bars and mechanism for operating said type-bars, a pair of supports, an arm pivotally mounted on each support, a contact member connected with and extending between said arms, and adapted for movement with said arms, said contact member extending below said mechanism, a lever pivotally mounted on each of said supports be-

low said arm, links connecting said levers with said arms, a spring connected to each of said levers for normally retaining said arms and contact member in lowered position, and a cross bar connecting said levers at their outer operative ends to afford simultaneous movement of same whereby a downward movement of the outer ends of said

levers will cause an upward movement of said arms with the connecting contact member into engagement with underside of said mechanism to thereby release the engaged type-bars. ¹⁰

In witness whereof I affix my signature.

JOHN HILGERT.
